UNITED STATES PATENT OFFICE.

JOSEPH E. MILLER, OF ROANOKE, VIRGINIA.

TRAFFIC-DIRECTOR.

1,368,185.

Specification of Letters Patent.

Patented Feb. 8, 1921.

Application filed May 28, 1920. Serial No. 385,004.

To all whom it may concern:

Be it known that I, JOSEPH E. MILLER, a citizen of the United States, residing at Roanoke, in the county of Roanoke and 5 State of Virginia, have invented certain new and useful Improvements in Traffic-Directors, of which the following is a specification.

This invention relates to traffic directors 10 for use particularly at intersecting city streets and has for its object to provide an improved device of this character. With this object in view, the invention consists of the formation, combination and arrangement 15 of parts as will be herein described and particularly claimed.

In the accompanying drawings, Figure 1 is an end elevational view of a preferred embodiment of the traffic director of my invention, the standard or supporting column being shown as broken in order to reduce the size of the drawing. Fig. 2 is a plan view of the same device. Fig. 3 is a horizontal sectional view through the upper portion 25 of the column, taken on the line 3—3 of Fig. 1. Fig. 4 is a similar view taken through the lower portion of the column on the line 4—4 of Fig. 1. Fig. 5 is a broken side elevational view of the device, similar 30 to the view of Fig. 1. Fig. 6 is a view of a diagrammatic nature showing how the signals may be operated from a remote position. Fig. 7 is an irregular horizontal section taken through the upper portion of the 35 column, this figure showing in a slightly enlarged scale some of the details of construction.

Referring to these drawings, the device 40 consists of a central post or supporting column 10, of tubular form, to the upper portion of which are attached four screens or shields 11, one of which extends radially from each quarter of the standard 10. The shields are made with an inner portion of 45 arcuate form arranged to match with the outer periphery of the column and from this two plate portions 12 extend radially outward. These plates 12 of one shield are spaced slightly from each other so that there 50 is provided between them a space 13 which accommodates a swinging signal, to be described later.

Each of the plates 12 has vertical guides upon its inturned face and along the edges

of the same. These are arranged to slidably 55 accommodate the plates 14.

These latter plates constitute signals which will be displayed through sight apertures 15 in the plates 12 when the plates 14 are lowered, and will be hidden behind solid 60 portions 16 of the plates 12 when raised.

Positioned beneath the apertures 15 are 65 slidable screens 17, these being formed of bent plates having arcuate central portions 18 with outstanding wings 19 arranged at right angles with each other. The wings of 70 one screen are arranged to overlie adjacent plates 12 of two shields 11.

The shields 11 are secured to the column 75 10 near their upper and lower edges by means of the rivets 20. At the central portion of these shields the metal is cut away to form a space 21 circumferentially of the column. Slidable within this space is a 80 column encircling band 22 to which the screens 17 are attached, the space 21 being long enough to allow the wings 19 to be moved into positions to cover the sight apertures 15 or to be lowered to positions in front of the solid portions 23 of the plates 85 12. A rod 24 is attached to the band 22 and extends downward to the position of the operator. By means of this rod the screens 17 may be moved to either position desired.

Hinged to the column above the shields 11 90 at 25 are four signal paddles 26. These are arranged to be swung from a depending position between the plates 12 and between the signal plates 14, where the signals 26 are obscured, to a horizontal outstanding position, 95 radial to the column, where the signals are displayed. The four paddles 26 are disposed at right angles about the column in planes coinciding with the general planes of the shields 11. When the paddles 26 are dropped it will be seen that they fall within the intervals arranged for that purpose in the shields 11.

The signal plates 14 and 26 are arranged 100 with different traffic directions, such as "Go" and "Stop," and in general the device is arranged so that from opposite fields of vision such as north and south one set of paddles, or one traffic order will be visible while at the same time from two other fields of vision 105 such as east and west the opposite traffic order will be visible.

The mechanism for operating the signals is

so arranged that the signals for north and south traffic and for east and west traffic may be operated independently or interlocked to automatically give the above described display of signals for the two streams of traffic. "Stop" or "Go" signals are displayed in all directions, there being four each of these legends for each of the two streams of traffic. From any single field 10 of vision the "Stop" and "Go" signals are so coupled together that when the one is displayed the other is hid. Also when the paddles 26 are lowered, all legends may be hid by means of the screens 17. All four of the 15 paddles 26 may be displayed at one time, stopping all traffic.

The operating mechanism extends upward within the cavity of the column 10 which is formed of a piece of pipe with suitable slots 20 in the walls thereof. Near the bottom of the column and pivoted at 27 within the cavity thereof are two operating levers 28 and 29. These are positioned side by side and the 25 portions thereof exterior of the column are operatively connected by means of the handle 30. This handle is formed as a tube which fits over the ends of the two levers. The lever 28 being of greater length than the lever 29, the tubular handle 30 may be withdrawn to a position to release lever 28 and the two levers may then be operated independently. With the handle 30 in position embracing both levers the two are operated 30 as a unit. The lever 28 has a stop shoulder 35 31 which is engaged by an inwardly extending set screw 32 in the handle to prevent its complete removal from the lever 28 unless desired.

The lever 28 is arranged to operate one set 40 of signals, such as north and south, and the lever 29 to operate the other set, such as east and west. Each lever is provided with a positioning spring 33 inside the column. These springs are pivoted at their lower 45 ends at 34, and coöperate at their upper ends with arms 35 from the levers to hold the entire mechanism in either of their positions.

In Fig. 1 the levers 28 and 29 are shown 50 as interlocked. In Fig. 5 the lever 29 is indicated in dotted lines as in position opposite from that of Fig. 1. The lever 28 operates the signals visible in Fig. 1 and lever 29 those visible in Fig. 5. Lever 28 55 is of the first class and lever 29 of the third class, hence when both levers are interlocked and moved in one direction as a unit it will be seen that one set of signals will be raised and another set lowered. Operating rods 60 36 extend inside the column 10 from the points 37 and 38 on the levers 28 and 29 respectively to near the top of the column. Here each of the rods is bifurcated with arms 39 and 40 to which are attached at 41 65 and 42 short lever like extensions 43 which

are secured to each of the paddles 26. When the rods 36 are lowered the attached paddles 26 are raised or displayed. A link 44 extends from the pivot point 45 on each paddle 26, to the top of the coöperating plate 14, hence movement of the paddles 26 about their pivots 25 will cause a corresponding sliding movement of the attached plates 14. Dropping of the signals 14 moves the signals 14 into view and raising 75 of them raises the signals 14 to position behind the plate portions 16.

A dome 51 may surmount the column for weather protection and appearance.

In Fig. 6 is shown how the signals may 80 be remotely controlled. A column or standard 46 is located at the point of control and levers 47 and 48 are applied in a similar manner as heretofore described except that cables 49 are carried downward and through 85 a conduit and then upward through a column 50, to which the signals may be applied as before.

Thus has been described a preferred embodiment of the invention. Other embodiments are contemplated, within the scope of the appended claims, without departing from the spirit of the same.

What is claimed is;

1. In a traffic director, a signal for indicating a traffic movement and another signal for indicating a different traffic movement, a support for the signals, the one signal being arranged for pivotal movement with respect to its support and the other for sliding movement with respect thereto, and means connecting the said signals whereby movement of one of the same will produce simultaneous movement of the other.

2. In a traffic director, a support, a signal pivotally connected thereto, a second signal slidably mounted thereupon, and interlocking means connecting the signals for the alternate display and obscurement of the two signals.

3. In a traffic director, a signal for indicating a certain movement of traffic, a second signal for indicating a different movement of traffic, means for operating the signals, the same being so arranged that when one signal is displayed the other will be hid, and independent means for hiding the other signal.

4. In a traffic director, a set of signals faced in one direction and a second set faced in a direction at an angle thereto, means for operating the first set of signals, and independent means for operating the second set, and means for interlocking the two said operating means in such manner that both sets of signals may be operated by one of the said operating means.

5. In a traffic director, a set of signals faced in one direction and a second set faced

in a direction at an angle thereto, independent means for operating the two sets of signals, and interlocking means for operating the two sets of signals as a unit, the same being so arranged that when one set is displayed the other will be hid.

6. In a traffic director, a signal bearing a certain traffic order, a second signal bearing

a different traffic order, means for displaying one signal and at the same time obscuring the other, and a slidable shield arranged to be moved into and out of position in front of one of the signals when in its displayed position.

In testimony whereof I affix my signature. 15

JOSEPH E. MILLER.
